Inventor:
Edward P. Hamilton
By G. A. Bragg Atty.

UNITED STATES PATENT OFFICE

EDWARD P. HAMILTON, OF TWO RIVERS, WISCONSIN, ASSIGNOR TO HAMILTON MANUFACTURING COMPANY, OF TWO RIVERS, WISCONSIN, A CORPORATION OF WISCONSIN

PRESS BOARD

Application filed August 1, 1928. Serial No. 296,852.

My invention relates to boards which are bound by strip material such as brass, the invention being of particular service in the formation of press boards used in book binding, though the invention is not to be thus restricted.

In accordance with one characteristic of the invention, the board, preferably though not necessarily of wood, is grooved between its broad faces and the binding for the board has a rib formation entering said groove. The binding preferably completely circumscribes the board which is also preferably the case with the rib formation and groove. 15 In accordance with another characteristic of the invention, interlocking formations are provided upon the contiguous ends of the binding for the board to hold these ends at the same level with respect to each other and 20 with respect to the board, a feature of especial importance where the board binding is wider than the thickness of the board and projects beyond both of its broad faces. The binding of a board applied in accordance with 25 my invention is well guarded from disarrangement both with respect to the component parts of the binding and with respect to the board.

The invention will be more fully explained 30 in connection with the accompanying drawing in which Fig. 1 is a perspective view of a press board bound in accordance with the preferred embodiment of the invention; Fig. 2 is a perspective view illustrating a broken 35 away portion of the structure with parts thereof in separated relation; and Fig. 3 is a side view with parts broken away.

The board 1 is preferably but not necessarily of wood. It is grooved upon its edges 40 and midway between its broad faces as indicated at 2, the groove formation preferably completely circumscribing the board. This groove is preferably angular in cross section with the sides thereof perpendicular to the 45 bottom thereof that is preferably flat. Four strips 3, 4, 5 and 6 of brass or other suitable material are applied to the edges of the board, these strips being wider than the thickness of the board and projecting beyond both broad 50 faces thereof when the structure is embodied

in a press board for book binding or other like purpose. Said strips project to equal extents beyond both broad faces of the board to constitute flanges for producing the hinge forming creases in the backs of the books between which the board is suitably clamped.

The binding is positioned by means of the inner rib formation 7 that extends along the binding and is pressed from each of the strips 3, 4, 5 and 6 and which corresponds in shape to the shape of the groove to be snugly received in the groove. In making the rib formation an external channel 8 is formed in register therewith. This channel 8 may serve to receive, preferably fully, the heads of assembling screws 9, if such be employed to fasten the binding in place. Hitherto the strips 3, 4, 5, 6 were apt to be shifted laterally of the board so as to extend unequal distances beyond the board which would cause some of the creases in the book backs to be too deep and the others not deep enough. I overcome this tendency by the provision of the grooves 8 and the formation of said strips with motion resisting portions that are snugly received in said grooves.

Interlocking formations are provided at the adjacent ends of the strips to hold the strips level or in a fixed plane with respect to each other and with respect to the board. These interlocking formations are desirably in the nature of tongues 10 and notches 11. As illustrated, each of the strips 3 and 5 is provided with a tongue 10 at each end thereof and each of the strips 4 and 6 is provided with a notch 11 at each end thereof, each tongue being snugly received in a contiguous notch to prevent lateral movement of the adjacent ends of adjacent strips for the purpose which has been stated. Each tongue 10 is desirably wider than the rib 7 and extends upon both sides of the rib which is thus formed, in part, of the tongue.

I have illustrated four separately formed strips upon the edges of the board but, obviously, the invention need not be thus limited nor need it be limited to the rectangular shape of the board.

Changes may be made without departing from the invention.

Having thus described my invention, I claim:

1. A board having a groove in its edge portion and between its broad faces, in combination with a binding of strip material projecting to equal extents beyond such broad faces and formed with an inner rib snugly received in said groove.
2. The structure of claim 1 wherein an external channel is formed in the binding and in register with the rib and fastening screws are passed through the rib into the board and having heads which are received in the channel.
3. The structure of claim 1 wherein adjacent end portions of the strip material constituting the binding have interlocking formations serving to prevent shifting of such end portions laterally of the binding.
4. The structure of claim 1 wherein adjacent end portions of the strip material constituting the binding are respectively formed with a tongue and a notch snugly receiving the tongue to prevent shifting of the end portions laterally of the binding.
5. The structure of claim 1 wherein an external channel is formed in the binding and in register with the rib and fastening screws are passed through the rib into the board and having heads which are received in the channel and wherein adjacent end portions of the strip material constituting the binding have interlocking formations serving to prevent shifting of such end portions laterally of the binding.
6. The structure of claim 1 wherein an external channel is formed in the binding and in register with the rib and fastening screws are passed through the rib into the board and having heads which are received in the channel, and wherein adjacent end portions of the strip material constituting the binding are respectively formed with a tongue and a notch snugly receiving the tongue to prevent shifting of the end portions laterally of the binding.
7. A board in combination with a binding of strip material projecting to equal extents beyond the broad faces of the board, said board and binding having snugly interfitting rib and groove formations extending along the board and between its broad faces.

In witness whereof, I hereunto subscribe my name.

EDWARD P. HAMILTON.
